(57) **CLAIM**

The ornamental design for a travel mug, as shown and described.

DESCRIPTION

FIG. 1 is a front perspective view of a travel mug with a cap; FIG. 2 is a front elevational view of the travel mug with the cap;

FIG. 3 is a rear elevational view of the travel mug with the cap;

FIG. 4 is a right-side elevational view of the travel mug with the cap;

FIG. 5 is a left-side elevational view of the travel mug with the cap;

FIG. 6 is a top view of the travel mug with the cap;

FIG. 7 is a bottom view of the travel mug with the cap;

FIG. 8 is a rear perspective view of the travel mug with the cap;

FIG. 9 is a front perspective view of the travel mug with the cap; and,

FIG. 10 is a rear perspective view of the travel mug with the cap.

The evenly-dotted broken lines in the drawings represent parts of the article that form no part of the claimed design. The dash-dot-dash broken lines in the drawings represent boundaries of unclaimed portions of the article that form no part of the claimed design.

1 Claim, 9 Drawing Sheets

Related U.S. Application Data

a continuation of application No. 29/608,704, filed on Jun. 23, 2017, now Pat. No. Des. 816,399.
